[57] CLAIM

The ornamental design for a reference power module

DESCRIPTION

FIG. 1 is a rear and upper left isometric view of a reference power module for measuring light energy entering an optical fiber splice showing our new design with the cover separated for the purposes of a complete disclosure;

FIG. 2 is a left end elevational view thereof with the cover shown in cross-section taken along line 2 of FIG. 3;

FIG. 3 is a rear elevational view thereof;

FIG. 4 is a top plan view of a reference power module for measuring light energy entering an optical fiber splice shown with the cover removed for convenience of illustration;

FIG. 5 is a front elevational view thereof;

FIG. 6 is a right end elevational view thereof;

FIG. 7 is a bottom plan view thereof;

FIG. 8 is a rear and upper left isometric view of a reference power module for measuring light energy entering an optical fiber splice showing our new design assembled;

FIG. 9 is a rear elevational view thereof;

FIG. 10 is a left end elevational view thereof;

FIG. 11 is a top plan view thereof;

FIG. 12 is a front elevational view thereof;

FIG. 13 is a left side elevational view thereof with the cover shown in cross-section taken along line 13 of FIG. 9; and,

FIG. 14 is a rear elevational view thereof, with the cover shown in cross-section taken along line 14 of FIG. 10.
